UNITED STATES PATENT OFFICE.

RUDOLF GOTTFRID NILSON RAHNE, OF GOTTERBORG, SWEDEN.

FINGER-BOARD FOR VIOLINS.

1,348,894.

Specification of Letters Patent. Patented Aug. 10, 1920.

Application filed January 2, 1919. Serial No. 269,329.

To all whom it may concern:

Be it known that I, RUDOLF GOTTFRID NILSON RAHNE, a subject of the King of Sweden, residing at Gottenborg, in the county of Gottenborg and Bohus and Kingdom of Sweden, have invented new and useful Improvements in Finger-Boards for Violins, of which the following is a specification.

10 This invention relates to finger boards for violins and as the primary object thereof consists in the provision of a device designed to be of assistance in instructing beginners to play a violin or other similar 15 stringed instrument and facilitate the teaching of the proper position of the fingers. The invention consists of metal pieces or other similar members provided with elevations, recesses or other suitable marks 20 positioned upon the finger-board close to the strings, so that the marks are easily perceptible to the player.

According to the present invention the marking members consist of metal ribbons 25 which are so attached to the fingerboard of the violin so that one ribbon will lie next to each string, thus enabling the player to locate the proper note, the same being indicated by the marks on the ribbons. The 30 vibrating strings do not come in contact with the ribbons. Furthermore the marked ribbons are arranged so as to be easily of different instruments.

The accompanying drawing shows an embodiment of the invention, provided for violins.

Figure 1 shows a plan view of the neck portion of a violin with the improved finger-guide applied,

40 Fig. 2 a side-view of the same parts, Fig. 3 shows a detail in cross-section and Fig. 4 the same detail in plan-view.

The apparatus is provided with two clasps 1 and 2, between which are extended 45 a plurality of metal ribbons 3, corresponding to the number of strings 10, said ribbons being provided with stamped marks or elevations 4. When applied to the finger-board one ribbon lies alongside each of the 50 strings 10. The marks 4 are spaced at a certain distance from each other, for instance, corresponding to the distance of the notes. The outer clasp 1 is attached to the head 5 of the violin and the inner 55 clasp 2 to the bottom of the neck of the violin, for which purpose the clasps are

provided with a stationary flange or tongue 12 and a slidable flange or tongue 13, actuated by a thumb screw 14, by means of which the sliding flange 13 can be moved 60 toward the stationary flange 12 and thereby clamp the clasp upon the neck of the violin, as illustrated by dotted lines in Fig. 3.

In order that the improved device may be adapted to be used upon violins of various 65 sizes and designs, the distance between the ribbons 3 must be adjustable to correspond to the distances between the strings 10. For this reason the ends 6 of the ribbons 3 in the embodiment of the invention, as clearly 70 illustrated by Figs. 3 and 4, are given an angular shape and are slidably arranged in the sides 7 of the clasp 1, thus projecting outside of this clasp. By pushing in or withdrawing the ends 6, the ribbons 3 are 75 adjusted into their proper position in relation to the strings 10, and may be locked in this position by means of a thumb-screw 8, acting on a plate 9, and thus the ends 6 of the ribbons are secured against the bottom 80 surface 11 of the clasp 1. The inner clasp 2 and the corresponding ends of the ribbons 3 may also be arranged in a similar manner, if it be considered expedient. To facilitate the sidewise adjustment of the ribbons 85 it is convenient to divide each ribbon in two portions 15 and 16, whereby the one portion 15 constitutes the ribbon proper and the other portion 16 the end portion, which is fitted into the clasp 2. The two ribbon portions 15 and 16 are joined together by means 90 of a joint 17, so that no breaking stress will be set up in the ribbons when adjusting their sidewise distances.

The ribbons 3 are applied so close to the 95 several strings 10, that the fingers of the player, when touching a string will at the same time touch the adjacent ribbon 3. A device of standard size may be employed, and the requisite adjustment of the distance 100 between the finger positions is effected by a slight displacement upward or downward of the bridge of the violin. Although the device according to the embodiment shown in the accompanying drawing has for its 105 object to serve as a guide only for the first position, there is nothing to prevent it from being extended by lengthening the ribbons 3. The invention is not limited to the embodiment described above, but changes in 110 the details may be made provided such changes are within the scope of the claims.

Having thus described my invention, what I claim is:

1. A finger-guide for violins comprising a plurality of metal ribbons, one for each of the strings, each ribbon being provided with a series of tangible marks easily perceptible to the touch of the fingers, and means to hold the ribbons upon the finger-board each obliquely below its proper string 10 in such a manner that the string when pressed down during the playing will not touch the marked ribbon, substantially as described.
2. A finger-guide for violins comprising a plurality of tangibly marked ribbons applied to the fingerboard of the instrument, one ribbon alongside of each of the strings, clamping members to hold the ribbons on the fingerboard, the ends of the ribbons being slidably mounted in said clamping members so that the distances between the ribbons may be adjusted to suit the distances 20 between the strings of the instrument.

3. A finger-guide for violins comprising a plurality of tangibly marked ribbons applied to the finger board of the violin alongside the strings thereof and having the ends bent angularly, clamping members attached to the finger-board near the ends of the ribbons, each including a stationary member and a movable member, the bent ends of the ribbons being arranged between the stationary and movable parts of the clamping members and set screws for forcing the movable clamping members toward the bent ends of the ribbons so as to hold the bent ends of the ribbons against the stationary members of the clamping members, substantially as described and for the purpose set forth. 35

In testimony whereof I have affixed my signature in presence of two witnesses.

RUDOLF GOTTFRID NILSON RAJNE.
